CUT-OUT SWITCH

Norman D. Benson, Iron Mountain, Mich.

Original application June 8, 1939, Serial No. 278,155. Divided and this application February 14, 1940, Serial No. 318,933

5 Claims. (Cl. 260—59)

This invention relates to vehicle direction signals and is a division of my copending application, Serial No. 278,155, filed June 8, 1939.

An object of this invention is to provide an improved switch structure for use with a vehicle direction signal system for closing an electric circuit to a number of signal devices mounted on the vehicle upon change in direction of the vehicle.

Another object of this invention is to provide an improved circuit making and breaking means connected to the steering mechanism of a vehicle which is adapted to automatically break the electric circuit in which the switch is interposed when the vehicle returns to a normal or a straight position.

A further object of this invention is to provide in combination a signal operating switch structure for closing an electric circuit to one or more signal devices on the vehicle upon change in direction of the vehicle and to provide a normally closed switch structure which is adapted to be interposed in a second signal circuit and which is adapted to break the second signal circuit when the vehicle returns to a straight or normal position.

A still further object of this invention is to provide a normally closed switch structure adapted to be interposed in an automatically operable signal circuit which is adapted to maintain the signal circuit closed during the change in direction of the vehicle but which upon return of the vehicle to a normal or a straight position, is adapted to momentarily break the automatic signal system and to thereafter close the circuit to the automatic signal system.

To the above objects and to others which may hereinafter appear, the invention consists of the novel construction, combination and arrangement of parts as will be more specifically referred to and illustrated in the accompanying drawing wherein is shown an embodiment of this invention, but it is to be understood that changes, variations and modifications may be resorted to which fall within the scope of the invention as claimed.

In the drawing:

Figure 1 is a detailed side elevation partly broken away and in section of a combination switch structure constructed according to an embodiment of this invention.

Figure 2 is a sectional view partly broken away and partly diagrammatic taken on the line 2—2 of Figure 1.

Figure 3 is a sectional view taken on the line

3—3 of Figure 1 and also showing diagrammatically the connections of the switch structure embodied in this figure.

Figure 4 is an enlarged fragmentary sectional view taken on the line 4—4 of Figure 3.

Figure 5 is an enlarged fragmentary sectional view taken on the line 5—5 of Figure 4.

Referring to the drawing, the numeral 10 designates generally a housing which is adapted to be fixedly secured to a selected part of the motor 10 vehicle structure. The housing 10 comprises a cup shaped body 11 having a boss or bearing 12 provided with a flange 13 which is fixed by fastening devices 14 to one end of the cup shaped member 11. The opposite end of the cup shaped member 11 is provided with a flange 15 and a closure plate 16 is adapted to be secured in any suitable manner to the flange 15 so as to close the housing 10.

A shaft 17 is journaled through the bearing or boss 12 and one end of an operating arm 18 is secured to the shaft 17. The closure plate 16 is also provided with a blind bearing 12^a in which the shaft 17 is also journalled. The arm 18 preferably is provided with a pair of clamping members 19 which are secured by a tensioning bolt 20 about the shaft 17. A connector 21 is secured to a reduced portion 22 of the shaft 18 and one end of a link 23 is pivotally secured as at 24 to the connector 21. A clamp 25 is adjustably mounted on a tie rod 26 forming part of the steering mechanism and the clamp 25 is provided with a pair of ears 27 between which the opposite end of the link 23 engages. A pivot member 28 engages through the ears 27 and through the opposite end of the link 23 is held against endwise movement by means of a cotter pin 29.

An insulated disc 30 is fixed to the shaft 17 in the housing member 11 and is provided on the periphery thereof with a pair of arcuate contacts 31 and 32. The contacts 31 and 32 have their confronting ends spaced apart, and these contacts comprise bridging contacts as will be hereinafter described. A wiper 33 is disposed within the housing member 11 and yieldably engages the contact 31. The wiper 33 is secured to the housing member 11 by means of a terminal bolt 34 which is insulated from the housing 11 by insulating members 35 and 36. The terminal 34 is connected by means of a conductor 37 to one side of an ignition switch structure 38 and the other side of the switch structure 38 is connected by a conductor 39 to a battery B. The battery B is grounded to the frame of the vehicle by means of 55

a conductor 40. A second wiper 41 is disposed within the housing member 11 spaced from the wiper 33 and is secured to the housing 11 by means of a terminal bolt 42. The bolt 42 is insulated from the housing 11 by means of insulating members 43 and 44. A pair of signal devices 45 and 46 are disposed at one side of the vehicle, the signal devices 45 being positioned at the front of the vehicle and the signal device 46 being positioned at the rear of the vehicle. The two signal devices 45 and 46 have one side thereof grounded by means of conductors 47 and 48, respectively, and a conductor 49 connects the opposite sides of these signal devices together. A conductor 50 is connected at one end to the conductor 49 and at the opposite end to the terminal 42. In this manner with the ignition switch on or closed when the bridging contact 31 engages the two wipers 33 and 41, a circuit will be completed to the two signal devices 45 and 46 from the switch 38, conductor 37, terminal 34, wiper 33, contact 31, wiper 41, terminal 42, conductor 50, and conductor 49.

A second pair of wipers 51 and 52 are mounted within the housing member 11 and are adapted to engage the arcuate contact or bridging member 32. The wiper 51 is secured to the housing member 11 by a terminal bolt 53 which is insulated from the housing member 11, and the wiper 52 is secured to the housing member 11 by a terminal bolt 54 which is also insulated from the housing member 11. The terminal 53 is connected to the conductor 37 and the terminal 54 is connected by means of a conductor 55 to a conductor 56. The conductor 56 connects a pair of front and rear signal devices 57 and 58, respectively, together. The signal device 57 has one side thereof grounded by means of a conductor 59 and the signal device 58 has one side thereof grounded by means of a conductor 60. In Figures 3, 4, and 5, there is disclosed a second switch structure which is mounted within the housing 10 and which is adapted to be interposed in the automatic signal circuit embodied in my co-pending application filed of even date herewith and also my copending application, Serial No. 278,155.

A pair of spaced apart contacts 61 and 62 are mounted within the housing member 11 and the contact 61 is provided with a base plate 63 through which a terminal bolt 64 engages. The plate 63 and the bolt 64 are insulated from the housing member 11 by insulating members 65 and 66, respectively. The contact member 62 is provided with a base plate 67 through which a terminal bolt 68 engages and the plate 67 is insulated from the housing member 11 by means of an insulating member 69. The bolt 68 is insulated from the housing member 11 by an insulating member 70.

A bridging contact 71 is disposed in laterally spaced relation to the contacts 61 and 62 and includes a stem or support 72 which is fixed to a base plate 73 insulated from the housing member 11 by an insulating strip 74. The base plate 63 is insulated from the base plate 73 by the insulating member 65. Likewise the base plate 67 is insulated from the base plate 73 by the insulating member 69. The terminal bolt 64 engages through the base plate 63 and through an oversize or clearance hole in the base plate 73 and is insulated from the housing member 11 by the insulating member 66 and holds the contact member 61 and one end of the bridging contact member 71 within the housing member 11. Likewise

the terminal bolt 68 engages through the base plate 69 and through an oversize or clearance hole in the base plate 73 and is insulated from the housing member 11 by the insulating member 70 and holds the other end of the bridging member 71 and contact 62 in housing member 11. The bolts 64 and 68 engage through the base plate 73 so as to hold the plate 73 tightly within the housing member 11.

A rock arm 75 is disposed within the housing member 11 and is provided with a bifurcated part 76 which engages between a pair of ears 77 carried by a base block 78. The block 78 is fixed to the interior of the housing member 11 by a fastening device 79. The housing member 11 has an elongated hole for the fastening device or screw 79, making the block 78 adjustable. The rock lever 75 is pivotally mounted between the ears 77 by means of a pivot member 80. The free end of the rock arm 75 is provided with a wiper 81 which is insulated from the arm 75 by an insulating member 82. The wiper 81 engages normally between the contact 61 and the bridging contact 71. A dog 83 is pivotally mounted between the bifurcated part 76 of the arm 75 being pivotally mounted on a pin or pivot 84 engaging between the bifurcations of the arm 75. The rock lever 75 is provided with a pair of extensions or stop members 85 which are adapted to engage the block 78 so as to limit the rocking or swinging movement of the arm 75 in one direction. A spring 86 is connected at one end to the dog 83 and at the other end engages a pin 87 carried by the block 78. The spring 86 normally urges the arm 75 inwardly with respect to the housing member 11 and also maintains the inner end portion of the dog 83 in engagement with the inner end of the bifurcated part 76 of the arm 75. A second rock arm 88 is mounted within the housing member 11 and is constructed in every detail similar to the arm 75. The rock arm 88 is provided with a bifurcated part 89 engaging between a pair of spaced apart ears 90 carried by a block 91 which is fixed by a fastening device 92 to the interior of the housing member 11. The housing member 11 has an elongated hole for the fastening device or screw 92 which holds the block 91 to the interior of the housing member 11. The block 91 and the block 78 are adjustable in a clock and counter clockwise direction. The arm 88 is pivotally mounted on a pivot member 93 engaging through the bifurcated part 89 and through the ears 90. The arm 88 is also provided with a pair of extensions or stop members 94 which are adapted to engage the block 91 so as to limit the inward swinging movement of the arm 88.

The free end of the rock arm 88 is provided with a wiper 95 engaging between the contacts 62 and 71 and the wiper 95 is insulated from the arm 88 by an insulating member 96. A pivoted dog 97 is rockably mounted between the bifurcations 89 of the arm 88 and one end of a spring 98 is connected to the dog 97. The opposite end of the spring 98 is mounted on a pin 99 carried by the block 91.

A lever tripping member 100 is carried by a sleeve or bushing 101 which is fixed by means of a pin or a key 102 to the shaft 17. The tripping member 100 is associated with the dog 83 and is adapted upon movement in a counter-clockwise direction to rock the dog 83 on the pivot 84 without rocking movement of the rock lever 75. After the tripping member 100 has moved past the inner end portion of the dog 83

and the rotation of the shaft 17 is reversed, the reversed movement of the tripping member 100 will cause the tripping member 100 to engage the free end of the dog 83 and effect rocking of the lever 75 without rocking of the dog 83 relative to the lever 75. Rocking of the lever 75 outwardly by engagement of the tripping member 100 with the dog 83 will cause the wiper 81 to be moved out of engagement with the contacts 61 and 71 so as to thereby break an electric circuit within which these contacts are interposed. A second tripping member 103 is carried by the bushing or sleeve 101 and is associated with the dog 97 and the lever 88. The operation of the tripping member 103 relative to the dog 97 is similar in every detail to the operation of the tripping member 100 relative to the dog 83 except that the tripping member 103 operates reversely from the tripping member 100. The terminal 64 is connected by means of a conductor 104 to an ignition switch structure 105 which is connected to a battery 106 having one side thereof grounded as by a conductor 107. The terminal 68 is connected to one end of a conductor 108 and the other end of the conductor 108 is connected to a switch structure generally designated as 109. The switch structure 109 is an electro-magnetic switch structure of the type wherein the switch is manually moved to a circuit closing position and is held in the circuit closing position by means of an electro-magnet 110. The details of the switch structure 109 and the electro-magnet 110 with its connections in a vehicle lighting system are more specifically described in my copending application filed of even date herewith. The switch structure 109 is of the type which is normally biased to a circuit breaking position so that when the circuit is broken to the coil or electro-magnet 110, the switch structure will be automatically moved to a circuit breaking position.

In the use and operation of this switch structure, the terminals 34 and 53 are connected together by means of the conductor 37, and are also connected to one side of a vehicle signal circuit embodying the signal devices 45, 46, 57, and 58. The terminals 42 and 54 are connected to the conductors 49 and 56 by the conductors 50 and 55, respectively. During the normal operation of the vehicle, the operating arm 18 will be disposed in the position shown in Figure 2 wherein the bridging contacts 31 and 32 engage only the wipers 33 and 51, respectively. However, upon turning of the vehicle to the right which is effected by movement of the tie rod 26 to the left as viewed in Figure 2, the contact carrying member 30 will rotate in a counterclockwise direction so as to engage the bridging contact 31 with the two wipers 33 and 51. At this time the circuit to the front and rear signal devices 45 and 46 will be closed from the switch 38, conductor 37, terminal 34, wiper 33, contact 31, wiper 51, terminal 42, conductor 50 and conductor 49, signal lights 45 and 46, conductors 47 and 37 to ground.

Where it is desired to signal a proposed change in the direction of vehicle before the change actually occurs, the electro-magnetic switch structure 109 is moved to the selected circuit closing position so as to close the electric circuits to the desired signal device which may be incorporated with the signal devices 45, 46, 57 and 58. The circuit to the selected signal devices will remain closed until the turn or change in direction has been completed whereupon one of the

tripping members 100 or 103 will rock its associated wiper carrying arm to a circuit breaking position. Where the vehicle turns to the right, the tripping member 100 will strike the dog 83 and rock this dog 83 on the pivot 84 without movement of the rock lever 75. The turn of the vehicle is such as to carry the tripping member 100 past the free end of the dog 83 so that when the vehicle returns to a normal or a straight position, this return movement will cause the shaft 17 to rotate clockwise and the tripping member 100 will contact with the dog 83. On the return movement of the tripping member 100, the contact of the tripping member 100 with the dog 83 will effect outward swinging of the wiper carrying arm 75 to a circuit breaking position without movement of the dog 83 relative to the arm 75. Outward rocking of the lever 75 will swing the wiper 81 out from between the contacts 61 and 71 thereby momentarily breaking the electric circuit to the switch structure 109. This momentary breaking of the circuit to the switch structure 109 will de-energize the electro-magnet 110 and thus permit the switch structure 109 to return under the action of its return spring to a circuit breaking position. After the tripping member 100 returns to the position shown in Figure 3, the spring 86 will return the wiper 81 to a circuit closing position which is the position shown in Figures 3, 4, and 5. 30

The operation of the rock lever 88 is reverse from that of the rock lever 75 and is effected upon turning of the vehicle to the left.

What I claim is:

1. A switch comprising an operating shaft, a housing on said shaft, a pair of spaced apart contacts carried by said housing, a rock arm, means pivotally mounting said arm in said housing, a wiper carried by said arm engaging between said contacts, a dog pivotally carried by said arm, a spring connected at one end to said dog and at the other end to a fixed part of the housing and constantly urging said arm to maintain said wiper to circuit closing position while holding said dog in operative position, and a dog tripping member carried by said shaft and operable upon rotation of said shaft in one direction to engage said dog to thereby rock said arm to circuit breaking position. 45

2. A switch for connection to the steering mechanism of a vehicle comprising a stationary housing, an operating shaft journalled in said housing, means connecting said shaft to the steering mechanism, a pair of spaced contacts carried by said housing, a bridging contact spaced laterally from said pair of contacts, a pair of rock arms, means rockably supporting said arms in said housing with the free ends thereof in confronting relation and between said contacts, a wiper carried by each arm engaging between one of said pair of contacts and said bridging contact, a dog pivotally carried by each arm, a spring engaging a dog and said housing yieldably holding a wiper in operative position, and a pair of tripping members fixed to said shaft, rotation of said shaft in one direction effecting contact between one tripping member and an associated dog without rocking of the arm to which said associated dog is pivotally secured, rotation of said shaft in the opposite direction effecting contact between said one tripping member and associated dog accompanied by rocking of an arm to thereby move a wiper into circuit breaking position. 60

3. A switch for connection to the steering mechanism of a vehicle comprising a stationary

housing, an operating shaft journalled in said housing, means connecting said shaft to the steering mechanism, a pair of spaced contacts carried by said housing, a bridging contact spaced laterally from said pair of contacts, a pair of rock arms each having a bifurcated part, means pivotally mounting said arms in said housing with the free ends thereof in confronting relation and between said contacts, a wiper carried by each arm engaging one of said pair of contacts and said bridging contact, a dog pivotally engaging between the bifurcated part of an arm, a spring engaging a dog and said housing yieldably holding a wiper in operative position, and 10 a pair of tripping members fixed to said shaft, rotation of said shaft in one direction effecting contact between one tripping member and an associated dog without rocking of the arms to which said associated dog is pivotally secured, rotation of said shaft in the opposite direction effecting contact between said one tripping member and associated dog accompanied by rocking of an arm to thereby move a wiper into circuit breaking position. 15

15. A switch for connection to the steering mechanism of a vehicle comprising a housing, an operating shaft journalled in said housing, means connecting said shaft to the steering mechanism, a pair of spaced contacts carried by said housing, a bridging contact spaced laterally from said pair of contacts, a pair of rock arms each having a bifurcated part, a pair of blocks fixed in said housing, a pair of ears carried by each block, means pivotally mounting a bifurcated part between said ears, the free ends of said arms engaging between said contacts, a wiper carried by and insulated from each arm and engaging between one of said pair of contacts and said bridging contact, a dog pivotally engaging between the bifurcated part of an arm, stop means carried by each arm engaging a block to limit the swinging movement thereof in one direction, a spring engaging a dog and said housing yieldably holding 20 a wiper in operative position, and a pair of tripping members fixed to said shaft, rotation of said shaft in one direction effecting contact between one tripping member and an associated dog without rocking of the arms to which said associated dog is pivotally secured, rotation of said shaft in the opposite direction effecting contact between said one tripping member and associated dog accompanied by rocking of an arm to thereby move a wiper into circuit breaking position. 25

20. rotation of said shaft in the opposite direction effecting contact between said one tripping member and associated dog accompanied by rocking of an arm to thereby move a wiper into circuit breaking position. 30

25. 4. A switch for connection to the steering mechanism of a vehicle comprising a stationary housing, an operating shaft journalled in said housing, means connecting said shaft to the steering mechanism, a pair of spaced contacts carried by said housing, a bridging contact spaced laterally from said pair of contacts, a pair of rock arms each having a bifurcated part, means pivotally mounting said arms in said housing with the free ends thereof in confronting relation and 35 between said contacts, a wiper carried by each arm engaging one of said pair of contacts and said bridging contact, a dog pivotally engaging between the bifurcated part of an arm, stop means carried by each arm limiting the swinging movement thereof in one direction, a spring engaging a dog and said housing yieldably hold-

ing a wiper in operative position, and a pair of tripping members fixed to said shaft, rotation of said shaft in one direction effecting contact between one tripping member and an associated dog without rocking of the arms to which said associated dog is pivotally secured, rotation of said shaft in the opposite direction effecting contact between said one tripping member and associated dog accompanied by rocking of an arm to thereby move a wiper into circuit breaking position. 5

5. A switch for connection to the steering mechanism of a vehicle comprising a housing, an operating shaft journalled in said housing, means connecting said shaft to the steering mechanism, a pair of spaced contacts carried by said housing, a bridging contact spaced laterally from said pair of contacts, a pair of rock arms each having a bifurcated part, a pair of blocks fixed in said housing, a pair of ears carried by each block, means pivotally mounting a bifurcated part between said ears, the free ends of said arms engaging between said contacts, a wiper carried by and insulated from each arm and engaging between one of said pair of contacts and said bridging contact, a dog pivotally engaging between the bifurcated part of an arm, stop means carried by each arm engaging a block to limit the swinging movement thereof in one direction, a spring engaging a dog and said housing yieldably holding 30 a wiper in operative position, and a pair of tripping members fixed to said shaft, rotation of said shaft in one direction effecting contact between one tripping member and an associated dog without rocking of the arms to which said associated dog is pivotally secured, rotation of said shaft in the opposite direction effecting contact between said one tripping member and associated dog accompanied by rocking of an arm to thereby move a wiper into circuit breaking position. 35

NORMAN D. BENSON. 40
